UNITED STATES PATENT OFFICE.

WILLIAM C. CARR, OF BUFFALO, NEW YORK.

TRANSPORTATION SYSTEM.

978,112.

Specification of Letters Patent.

Patented Dec. 6, 1910.

Application filed December 11, 1908. Serial No. 466,998.

To all whom it may concern:

Be it known that I, WILLIAM C. CARR, a citizen of the United States, residing at Buffalo, in the county of Erie and State of New York, have invented a certain new and useful Improvement in Transportation Systems, of which the following is a specification.

This invention relates to a transportation system, and the object of the invention is to simplify and improve systems of this class, to provide a strong and durable construction, and to insure certainty of operation.

The invention also relates to certain details of construction which will be herein-after described and perhaps claimed, reference being had to the accompanying drawings in which an adaptation of the invention is illustrated.

Figure 1 represents a side elevation of a fragment of an elevated track with a car supported thereby, and also showing a side view of a fragment of one of the supporting standards. Fig. 2 is a transverse section through the rails of a track with an end view of a car supported thereby and also showing a side view of a fragment of one of the supporting standards. Fig. 3 is an enlarged vertical section on line *a-a*, Fig. 1, through the brush contact employed in lieu of a trolley wheel and its supporting bracket, together with a transverse vertical section through the portions of the car frame to which the supporting bracket is secured. Fig. 4 is a fragmentary top plan view of the car frame with the brush supporting bracket attached thereto and a horizontal section through the brush on line *b-b*, Fig. 3.

In referring to the drawings in detail like numerals designate like parts.

A fragment of an elevated track composed of two parallel rails 1 and 2 is illustrated in Figs. 1 and 2, with the rails supported in elevated position by single vertical standards 3 having bifurcated top elements, to the branches of which the rails are fastened.

The bifurcated top elements each consist of a transverse member 4, having a central socket in which the upper end of the standard is secured and two upwardly extending bent ends and two vertical side members 5 and 6 having enlarged bases at their lower ends bolted to the upwardly bent ends of the transverse member 4, and inwardly curved upper ends which are bolted to the sides of the rails 1 and 2.

The rails are preferably of channel form in cross section with the groove or channel on the under surface of the rails, see Fig. 2, and the rails not only serve to support the car but are also connected to a source of electric power and act as a conducting medium for the electric current.

The car illustrated consists of two side frame members 7 and 8 between which a series of individual boxes 9 for mail or other purposes are removably supported, front and rear axles 10 and 11 journaled above the frame in vertically projecting brackets 12.

The electric motors 13 for operating the car are mounted directly on the front and rear axles 10 and 11.

Power is conveyed to the motors through brushes which have their upper ends in contact with the channeled under surface of the rails.

The brushes consist of a series of sections of wire 14, preferably spring piano wire, and a holder 15 having a metal socket in which the lower terminals of the wire sections are rigidly secured.

The holder 15 is formed of suitable metal and has an enlarged upper end or head 16 in which the socket for receiving the wire sections is located.

The holder is slidably mounted in a three membered bracket formed substantially as shown in Figs. 3 and 4, and having upper and lower members 17 and 18 which are secured by bolts or other suitable fastenings to a member of the car frame, and a laterally projecting member 19 which is provided with a vertical opening and a vertically projecting tubular portion or flange 20 in which the depending shank of the holder 15 is slidably mounted.

To yieldingly maintain the brush in elevated position a spiral spring 21 is interposed between the enlarged head 16 of the holder and the member 19 of the bracket, as shown in Fig. 3.

The shank of the holder is secured in the flanged opening in the bracket against removal by a locking pin 22 which is fitted through a transverse opening in the lower projecting end of the shank and extends on opposite sides of the shank sufficiently to catch against the bottom surface of the lateral member 19 of the bracket, as shown in Fig. 3.

Strips of insulating material 23 are inter-

posed between the supporting brackets and the car frame to prevent the electric current passing into the car.

The electric motors are electrically connected to the brush supporting brackets by conducting wires 24.

In practice, both of the rails 1 and 2 are electrically energized and serve as conductors of the electric current, and two brushes are employed for each motor, the supporting brackets of which are bolted to opposite sides of the car and maintain the upper extremities of the brushes in the channels of the respective rails. By this means two sources of electric transmission are employed, and the electric circuit is completed through the rails, the two brushes and the motor.

The wire sections of each brush are arranged in a bunch or bundle with the lower portion of the bunch or bundle secured rigidly in the socket of the holder and the upper portion free to bend or spring under pressure.

By referring to Fig. 1, it will be noted that the upper terminations of the brushes are forced against the lower surfaces of the rails with sufficient pressure to bend the wire sections of the brushes. This not only insures a perfect contact but also causes the brushes to clean the surfaces as the car travels, thereby permanently maintaining a perfect contact. The brushes likewise provide a multiplicity of contacts with a contacting surface of large area which minimizes the loss of electric energy in transmission and thus economizes power.

The wheels are insulated from each other to prevent short circuiting in any well known manner.

I claim:

1. The combination with a bracket, of a brush composed of a holder having a shank slidably mounted in said bracket, and an enlarged head provided with a socket, and a series of sections of spring wire having

their lower terminals rigidly mounted in the socket of said holder.

2. The combination with a bracket having upper and lower members adapted to be fastened to a car, and a lateral projecting member provided with a vertical opening, of a brush composed of a holder having a shank slidably mounted in the vertical opening in the lateral member of the bracket, and an enlarged head provided with a top socket and a series of spring wire sections arranged in a bunch with their lower ends rigidly fastened in the socket of the enlarged portion of the holder.

3. The combination with a bracket having a lateral projecting member provided with a vertical opening and a vertical tubular flange above said vertical opening, of a brush composed of a holder having a shank movably mounted in the vertical opening in the lateral member of the bracket, and an enlarged head provided with a top socket, a series of spring wire sections arranged in a bunch with their lower ends rigidly fastened in the socket of the enlarged portion of the holder, and a coil spring having its lower end fitted around the vertical tubular flange and its upper end bearing against the enlarged head of the brush holder.

4. The combination with a bracket having a vertical opening, of a brush composed of a holder having a shank slidably mounted in the vertical opening in the bracket and an enlarged head provided with a socket, a series of spring wire sections arranged in a bunch with their lower ends rigidly fastened in the socket of the enlarged portion of the holder, and a coil spring loosely surrounding the shank of the holder with its respective ends bearing against the bracket and the enlarged head of the holder.

WILLIAM C. CARR.
